UNITED STATES PATENT OFFICE.

FRANCIS M. ROSENFELD, OF NEW YORK, N. Y., ASSIGNOR TO IMPORT SALES COMPANY,
A CORPORATION OF NEW YORK.

PORTABLE ELECTRIC LAMP.

1,173,984.

Specification of Letters Patent. Patented Feb. 29, 1916.

Application filed March 5, 1915. Serial No. 12,406.

To all whom it may concern:

Be it known that I, FRANCIS M. ROSENFELD, a citizen of the United States, residing in the city, county, and State of New York, 5 have invented certain new and useful Improvements in Portable Electric Lamps, of which the following is a description.

My invention relates to electric lamps of the well-known portable or pocket type, 10 which are operated by means of a dry battery contained in a casing which may be partly or wholly metallic, and which casing carries, at some convenient point, a suitable switching mechanism for closing the lamp 15 circuit.

One of the principal objects of my invention is to provide means whereby one pole of the battery shall be completely insulated from the metallic portions of the casing, so 20 that the battery cannot be short-circuited or connection made through the lamp accidentally as, for instance, by contact of the casing, switch or portions thereof with a metallic body.

25 Further objects of my invention are to simplify the construction of the apparatus, thus making it cheap, easy to manufacture, and less liable to derangement, and to provide an efficient, simple means of completing 30 the circuit through the lamp.

Other objects of my invention will be pointed out in this specification and in the claims.

In the drawings accompanying this specification, I have shown in Figure 1 a side view of a lamp having a metallic casing and embodying my improvements. In Fig. 2 I have shown a sectional view of the lamp shown in Fig. 1. In Fig. 3 I have shown my 35 improvements applied to a lamp, the casing of which is partly metallic and partly insulated. Fig. 4 shows a detail plan view of the spring which contacts with one of the battery poles, and in Fig. 5 I have 40 shown a perspective view of one of the contact members to which the spring shown in Fig. 4 is connected.

Referring to the drawings, 1 indicates a battery, one pole of which, 2, is connected 50 to a pole 3 of the lamp 4. The other pole of the lamp 5 is connected to a metallic reflector 6, or otherwise electrically connected either to the metallic casing 7, if the casing is wholly metallic as in Fig. 2, or to a metallic strip 8, if the casing is partly of insu-

lating material. In either event, however, the connection is made to one element of the switch 9.

The details of the specific switch mechanism illustrated in Fig. 3 are fully shown 60 and described in my Patent No. 1,154,130, Sept. 21, 1915, for circuit-closing devices, to which reference is made for a fuller description.

The other pole of the battery 1, which in 65 this instance is the case of the battery, is connected to a spring 10 which is adapted to exert pressure against the battery to keep the pole 2 in contact with the lamp. Spring 10 is connected to a circular member 11, 70 which member is insulated from the casing by means of insulating washers 12 and 13. Member 11 is attached to the casing by means of a bolt or rivet 14 passing through insulating washers 12 and 13 and bearing 75 against an insulating disk 15. Insulating disk 15 is located on the inner side of member 11 and is preferably formed with a beveled edge for a purpose which will be hereinafter described. Member 11 has formed 80 upon it a plurality of upturned ears 16, which are perforated to enable the spring to be passed therethrough, as shown in Fig. 4, thus holding the insulating disk 15 in place during assembling. 85

It will thus be seen that while pole 2 of the battery is connected to metallic portions of the casing, the other pole of the battery is entirely insulated therefrom, so that it is impossible to short-circuit the battery or 90 close the lamp circuit without operating the switch.

The casing of battery 1 is, as is usual, insulated from the lamp casing by means of an insulating covering 17, and, if desired for 95 additional security, a second insulating covering 18 (Fig. 2) may be used.

In the modification shown in Fig. 2, the switch 9 operates in a slot 19 formed in the battery casing, so that it may be longitudinally slid thereon. Connected to the switch 9 is an extension 20, which is thus electrically connected to the metallic casing 7, and, through it, to the battery pole 2. When switch 9 is slid longitudinally toward the 105 rear of the lamp, extension 20 will ride up the bevel of insulating disk 15 and make contact with the edge of metallic member 11. If desired, the metallic member 11 may be so proportioned and the extension 20 so 110

formed that movement of the extension 20 to the limit of its movement will cause the end of extension 20 to enter in the space between the edge of metallic member 11 and 5 the casing immediately adjoining it, thus making contact at that point.

In the modification shown in Fig. 3, a connecting strip or other metallic piece 21, connected to another element of the switch 22 10 and bearing upon the edge of member 11, is provided. In this case a movement of the switch 9 in a forward direction will cause connection to be made between the two poles of the battery through the lamp 4. 15 In either modification, however, accidental short-circuiting of the battery or closing of the lamp circuit is prevented by the provision of the means described for completely insulating one of the battery 20 poles from the metallic portions of the casing.

While I have only shown one form of my invention, I do not intend to limit myself thereto, as it will be evident to those skilled 25 in the art that many modifications may be made without departing from the spirit of my invention.

What I claim is:

1. In a device of the character described, 30 a metallic casing, a battery mounted therein, a lamp mounted at one end of the casing and electrically connected thereto and to one pole of the battery, a cap detachably mounted at the other end of the casing, a disk 35 secured to and insulated from said cap and electrically connected to the other pole of the battery when the cap is in position, and a conductor slidably mounted within the casing and electrically connected therewith 40 and adapted when operated to contact with said disk to complete the circuit through the lamp.

2. In a device of the character described, 45 a metallic casing, a battery mounted therein, a lamp mounted at one end of the casing and electrically connected thereto and to one pole of the battery, a cap detachably mounted at the other end of the casing, a disk secured to and insulated from said cap, 50 a spring connected to said disk and adapt-

ed to form an electric connection between said disk and the other pole of the battery when the cap is in position, and a conductor slidably mounted within the casing and electrically connected therewith and adapted when operated to contact with said disk to complete the circuit through the lamp. 55

3. In a device of the character described, a metallic casing, a battery mounted therein, a lamp mounted at one end of the casing and electrically connected thereto and to one pole of the battery, a cap detachably mounted at the other end of the casing, a conducting element carried by said cap and electrically connected to the other pole of the battery when the cap is in position, an insulator interposed between said element and said cap, means passing through said insulator and insulated from said element for retaining said element and said insulator in position, and a conductor slidably mounted within the casing and electrically connected therewith and adapted when operated to contact with said element to complete the circuit through the lamp. 70 75

4. In a device of the character described, a metallic casing, a battery mounted therein, a lamp mounted at one end of the casing and electrically connected thereto and to one pole of the battery, a cap detachably mounted at the other end of the casing, a conducting element carried by said cap, an insulator interposed between said element and said cap, a spring held in position by said element and electrically connected thereto 80 and adapted to form an electrical connection between said element and the other pole of the battery when the cap is in position, and a conductor slidably mounted within the casing and electrically connected therewith and adapted when operated to contact with said element to complete the circuit through the lamp. 85 90

In testimony whereof I have signed this specification in the presence of two subscribing witnesses.

FRANCIS M. ROSENFELD.
